J. B. CORNELL.

DOUBLE CYLINDER FIREPROOF COLUMN.

No. 27,528.

PATENTED MAR. 20, 1860.

Fig. 1.

UNITED STATES PATENT OFFICE.

JNO. B. CORNELL, OF NEW YORK, N. Y.

DOUBLE-CYLINDER FIREPROOF COLUMN.

Specification of Letters Patent No. 27,528, dated March 20, 1860.

To all whom it may concern:

Be it known that I, JOHN B. CORNELL, of the city, county, and State of New York, have invented a new and Improved Fire-proof Column; and I do hereby declare that the following is a full and exact description thereof, reference being had to the accompanying drawings, making a part of this specification.

10 It is a well known fact that cast iron columns, when formed in the ordinary manner, are greatly weakened and sometimes utterly destroyed by the action of water when the said columns are in a highly heated state. This serious objection to cast iron columns caused me to institute a series of experiments in the hope of being able to produce an architectural column that would possess all the advantages of the ordinary 15 cast iron column, without any of its defects. My said experiments resulted in the production of an architectural column composed of two thin sided concentric tubes (*a* and *b*) of cast iron, combined with each other by 20 means of a solid mass of fire-proof composition run into the annular space between said tubes.

The united weight of the metallic tubes (*a* and *b*) of my improved column, need not 25 be greater than the weight of the ordinary cast iron column; and the thickness of the fire-proof composition (*c*), between the said tubes, need be only sufficient to afford the requisite protection to the inner tube, (*b*), 30 in case the outer tube (*a*) should be exposed to the action of fire in a burning building.

The inner tube (*b*) of my said improved column, must be strong enough to safely 35 support the entire weight that would be brought to bear upon it, in case the outer

tube (*a*) of said column, should be injured by the action of fire and water.

The outer tube *a*, of my said improved column, having very thin sides, has much 45 greater strength in proportion to its weight than the ordinary cast iron column; and another result of the thinness of the sides of the said outer tube, is that it will endure the action of fire and water with much less 50 danger of injury than the ordinary thick-sided cast iron column for architectural purposes. As cast iron has but little strength save at or very near to its surface, it will readily be perceived that my improved architectural column must possess 55 fully three times the stiffness and strength of an ordinary cast iron column containing the same amount of metal.

The tubular metallic portions *a*, *b*, of my 60 improved architectural column, may be made of any angular shape instead of the circular shape represented in the accompanying drawings.

What I claim as my invention and desire 65 to secure by Letters Patent, is—

Constructing an architectural column of two concentrically arranged cast iron tubes and an intermediate solid mass of fire-proof composition, when the said parts are combined with each other in such a manner as to form but a single article of manufacture which shall possess the characteristics herein set forth.

The above specification of my double cylinder fire-proof column, signed and witnessed this 27th day of July 1855. 75

JOHN B. CORNELL.
